(57) **CLAIM**

The ornamental design for a currency processing machine, as shown and described.

DESCRIPTION

FIG. 1 is a front view of a first embodiment of a currency processing machine showing my new design;

FIG. 2 is a rear view thereof;

FIG. 3 is a left side view thereof;

FIG. 4 is a top plan view thereof;

FIG. 5 is a bottom view thereof;

FIG. 6 is an upper right front perspective view thereof;

FIG. 7 is a front view of a second embodiment of a currency processing machine showing my new design;

FIG. 8 is a left side view thereof;

FIG. 9 is a top plan view thereof;

FIG. 10 is a bottom view thereof;

FIG. 11 is an upper right front perspective view thereof;

FIG. 12 is a top view of a third embodiment of a currency processing machine showing my new design;

FIG. 13 is a top view of a fourth embodiment of a currency processing machine showing my new design;

FIG. 14 is a top view of a fifth embodiment of a currency processing machine showing my new design;

FIG. 15 is a top view of a sixth embodiment of a currency processing machine showing my new design;

FIG. 16 is a top view of a seventh embodiment of a currency processing machine showing my new design; and,

FIG. 17 is a top view of an eighth embodiment of a currency processing machine showing my new design.

In each embodiment, a right side view is omitted because the right side view is symmetrical to the left side view.

In a second embodiment, a rear view is omitted because the rear view is identical to the one of a first embodiment.

In each of a third embodiment to an eighth embodiment, a front view, a rear view, a left side view and a bottom view are omitted because they are identical to the respective views in a second embodiment.

The broken lines in the drawings depict portions of the currency processing machine that form no part of the claimed design.
